UNITED STATES PATENT OFFICE.

STANTON W. FORSMAN, OF PASADENA, CALIFORNIA, ASSIGNEE TO R. W. PRIDHAM COMPANY, OF LOS ANGELES, CALIFORNIA, A CORPORATION OF CALIFORNIA.

SHIPPING-CONTAINER AND BOARD FOR CONSTRUCTING THE SAME.

1,161,818.

Specification of Letters Patent. Patented Nov. 23, 1915.

Application filed May 19, 1915. Serial No. 29,212.

To all whom it may concern:

Be it known that I, STANTON W. FORSMAN, a citizen of the United States, residing at Pasadena, in the county of Los Angeles and State of California, have invented 5 a new and useful Shipping-Container and Board for Constructing the Same, of which the following is a specification.

This invention relates to boxes and other 10 containers designed for protecting their contents from injury during shipment and storage and for holding together packages of goods, especially packages of canned goods for convenience of handling for shipment and for storage.

In the present state of the art, so far as I am advised, there have been provided for this purpose boxes of wood, and also boxes made of flat corrugated and cellular paste- 20 board of various kinds, and it has been customary to construct said boxes made of pasteboard in a collapsible form substantially such as I propose to employ in the most general embodiment of this invention.

It is an object of this invention to provide 25 a container of minimized weight and maximized protective qualities, the same being designed to resist to a comparatively maximum extent the stress and strain and destructive forces to which a package of goods, 30 heavy or light, is lightly to be subjected while being handled, stored or transported.

As an illustration of the practical result 35 of this invention, I will state that an object of this invention is to provide a container of minimum weight having a strength sufficient to sustain without liability of being crushed, a load of one thousand pounds distributed over an area of 9 by 14 inches, the 40 side dimensions of the container, so that containers constructed in accordance with this invention having outside dimensions of 9 by 14 by 5½ inches can be stacked in stacks such that the weight upon the top side of 45 the lower one of said containers in a stack may be one thousand pounds, more or less, distributed evenly over the top side of said bottom package without any danger of crushing the same; thus enabling the packages to be loaded into cars and stored in 50 warehouses with perfect safety for a predetermined height of stack.

Where the goods contained in the packages are cans of fruit, vegetables, meat, fish 55 and the like, the weight of each package is

considerable and it is an object to insure safety of the same, whether said cans be of glass or of sheet metal.

An object of the invention is to accomplish all of these advantageous results at a 60 minimum expense and with the usual apparatus and materials at the command of the ordinary box manufacturer.

All of these objects I have succeeded in accomplishing by this invention after a 65 period of about three years of careful application and experiment toward the solution of the problem.

The invention may be understood by reference to the accompanying drawings.

Figure 1 is a perspective view of a container constructed as a collapsible box in accordance with this invention and erected ready to receive the goods. Parts are broken away to expose the structure. Fig. 2 is an 70 enlarged piece of board from which boxes corresponding to the box shown in Fig. 1 may be constructed, parts being separated to illustrate the construction. Fig. 3 is an 75 enlarged sectional detail of a corner of a 80 box constructed in accordance with the invention. Fig. 4 is an enlarged section of the board of which boxes corresponding to said box shown in Fig. 1 may be constructed, both sides of the board being of three 85 ply.

In the drawing, I have shown a container having a cellular wall formed of four members, 1, 2, 3, 4, and end members 5, 6, forming continuations thereof to fold over and close the ends of the container. The wall is cellular, being constructed of an intermediate bent sheet 7, an inner facing sheet 8, and an outer indurated plural ply sheet 9, said sheets being united to form a cellular structure, substantially shown in Figs. 3 and 4; the inner members of the structure being crushed or creased as at 10 to allow the container to be constructed and erected or collapsed as occasion requires.

The inner facing 8 and the intermediate sheet 7 may be of paper or the like, as shown in Fig. 3 or the inner facing may be plural ply as shown at 8' in Fig. 4, and may be of any desired weight required for the 95 work in hand. The outer facing 9 is plural ply fiber paste-board and is preferably indurated, that is to say of a solid, firm and hard texture and construction, and of two or more plies pasted together so as to have 100 105 110

greater strength and rigidity than is called for by the requirements of the sheets 7 and 8. Said indurated sheet, in the form shown, is constructed of several plies of paper united together by silicate of soda, or other strong paste or cement. Said sheet 9 is preferably made of what is known as fiber board, in which the sheets *a*, *b*, *c* are paper made of strong fiber, such as jute or the like, and these three sheets are united by the silicate 10 coatings *d*.

The intermediate sheet is shown corrugated, but it is understood that any cellulated structure or form may be employed, 15 and that said sheet may be honeycombed, indented or otherwise formed with undulations, wrinkles, or irregularities, impressions, or cavities of such a character that when the three sheets are united, as shown 20 in Fig. 3, the board thus formed will be of cellular structure.

The sheets 7 and 8 may be of a soft and yielding character, and the air contained in the cellular body is confined by the folds 25 formed by bending the board transversely of the corrugations. Such folding closes the cells and confines the air in a well known manner so that the plural ply indurated outer facing 9 in combination with the 30 closed air cells, constitutes a sheet of unexpected strength and rigidity which is increased in the structure shown in Fig. 4.

The intermediate body 7 may be united to the facings 9 and 8 or 8' by any suitable 35 medium, either silicate, paste, glue or other cementing material.

The board may be constructed by cementing one side of an ordinary cellular paste-board formed of soft paper arranged with 40 two flat sides and an intermediate corrugated or other cell forming sheet of paper; the indurated facing being applied to one side of said board in one or more plies, united thereto by silicate, or other strong 45 cementing material.

By this invention I have provided a board having an indurated facing strengthened by a cellular structure united to one side thereof, said cellular structure having a plain 50 surface opposite the indurated facing, as clearly shown in Fig. 3.

I am aware that corrugated board has been manufactured and been in use for the making of shipping containers, I am also aware that two or more ply pasted fiber 55 board has been manufactured and used in the making of what is known as solid fiber shipping containers.

It is a novel and new invention to use a solid fiber board, (and what I mean as solid 60 fiber board, is two or more ply paper pasted together,) in connection with corrugated board, the advantages gained in constructing a corrugated board box using two or more ply pasted board for the faces, lie in 65 the fact that the pasted board is more rigid, tougher and less liable to be torn or punctured than a single ply pasted board and I have discovered that the combination of said two or more ply pasted fiber board with 70 the cellular board set forth, affords a solution of a problem heretofore unsolved, in that it affords a container of maximized strength and puncture resisting qualities combined with minimized weight. 75

I claim:

1. A container having a cellular wall constructed of an inner facing sheet of yielding sheet material, an outer indurated facing sheet formed of two or more plies of 80 paper pasted together and an intermediate bent sheet united to said inner and outer sheets.

2. The board set forth comprising facing sheets and an intermediate corrugated sheet 85 united together, one of the facing sheets being of two or more plies pasted together.

3. The board set forth comprising facing sheets and an intermediate corrugated sheet pasted together, one or both of the facing 90 sheets being of two or more plies pasted together.

4. The board set forth comprising facing sheets and an intermediate corrugated sheet pasted together; one of said facing sheets 95 being multiply.

In testimony whereof, I have hereunto set my hand at Los Angeles California this 10th day of May, 1915.

STANTON W. FORSMAN.

In presence of—

JAMES R. TOWNSEND.
